RUFUS G. FORDYCE, OF CHICAGO, AND HARRIE F. TALBOT, OF PERU, ILLINOIS, AS
SIGNORS TO RADIUM DIAL COMPANY, OF OTTAWA, ILLINOIS, A CORPORATION OF
ILLINOIS

MACHINE FOR PRINTING LUMINOUS DIALS

Application filed August 8, 1929. Serial No. 384,454.

This invention relates to dial-printing machinery, and more particularly to a machine for automatically printing luminous figures upon clock or watch dials.

One object of this invention is to provide a machine of the above nature in which the luminous material, which may contain radium, phosphorous or other ingredients, will be confined at all times to prevent drying up too rapidly.

A further object of this invention is to provide a machine of the above nature in which the luminous paint is supplied from a hopper to a cylindrical metal die from which it is removed by a soft transfer roll and printed upon the dial which is held on a reciprocating plate beneath said roll.

A further object is to provide a device of the above nature which will be simple in construction, inexpensive to manufacture, easy to manipulate, compact, and very efficient and durable in use.

With these and other objects in view there have been illustrated on the accompanying drawings two forms in which the invention may be conveniently embodied in practice.

Fig. 1 represents an end view of the dial-printing machine.

Fig. 2 is an end sectional view of the same, taken along the line 2—2 of Fig. 3, looking in the direction of the arrows.

Fig. 3 is a front view, partly in section, of the dial printing machine.

Fig. 4 is a perspective view of the cylindrical transfer die.

Fig. 5 is a fragmentary sectional view of the hopper and a portion of the cylindrical die.

In the manufacture of luminous dials in the past, it has been customary to manually apply the luminous figures or characters with a small paint brush. This operation was found to be extremely slow and was expensive to carry out.

Attempts have been made to avoid these disadvantages by devising mechanism for performing mechanically some of the steps of the painting process. A device of this nature was disclosed in Patent No. 1,657,237, granted January 24, 1928, to Harrie F. Tal-

bot, one of the joint inventors of the invention disclosed herein. While this patent disclosed a method to overcome the above-mentioned difficulties to a considerable extent, it did not completely solve the problem, as some of the steps of the dial-painting process still had to be performed by hand labor.

The present invention overcomes the above disadvantages, and eliminates almost entirely hand labor in connection with the painting of luminous figures upon watch and clock dials.

This has been accomplished by providing an improved machine having a hopper within which the luminous paint from which the figures are to be printed is first received. From the hopper, the paint is taken up by a rotary die, being forced thereupon by mechanically-operated brush. Provision is also made of a rubber cylindrical transfer roll adapted to rotate in contact with the cylindrical die for transferring the paint from the die to the dial which is carried on a reciprocating bed therebeneath.

After the luminous paint has been placed in the hopper, the operation is automatic, it being unnecessary for the operator to scrape the surface of the cylindrical die as was formerly required.

Referring now to the drawings in which like reference numerals denote corresponding parts throughout the several views, the numerals 10 and 11 indicate a pair of spaced platforms having frames 12 and 13 extending upwardly therefrom. Each of the frames 12 and 13 have central rectangular slotted sections 14 for adjustably receiving bearing blocks 15, 16, 17, and 18, respectively. The bearing blocks are slidably mounted in the sides of the slotted sections 14 and are adapted to support a pair of horizontal shafts 16a and 18a, the upper shaft 16a having rigidly mounted thereon a cylindrical die 19, preferably metallic, while the lower shaft 18a carries a resilient soft transfer roll 20 of a suitable composition, such as rubber or gelatine.

Mounted upon the top of the printing machine is a hopper 20a having downwardly converging side sections and inwardly in-

clined bottom sections 21 and 22. The inside edges of said bottom sections are beveled and spaced apart, as shown in Fig. 2, for fitting the periphery of the cylindrical die 19. The 5 top of the hopper 20a is closed by a horizontal detachable cover member 23, whereby the hopper may be readily charged with luminous paint.

The transfer roll 20 is adapted to rest in 10 contact with a dial 24 carried by a slidable reciprocating jig or dial block 24a, which in turn is carried by a sliding bed plate 25, the latter being mounted to reciprocate upon knife edges 26 and 27 carried by the platforms 15 10 and 11 respectively. The top bearing blocks 17 and 18 are provided with upwardly extending bars 25a and 26a having threaded sockets within which are mounted a pair of threaded bolts 27a and 28 which support a 20 pair of cross heads 29, each of which is held in place by a pair of wing nuts 30 and 31, whereby the position of said cross-heads 29 may be readily adjusted.

In order to force the luminous paint into 25 the engraved figures of the die 19, provision is made of a small upper shaft 32 having a brush drum 33 rigidly mounted thereon, said drum having a plurality of flexible blades 34 extending radially from its outer surface. 30 The blades 34 rest upon the top of the die 19 and are adapted to be forced thereagainst by a pair of springs 35, the ends of which are seated in sockets 36 and 37 in said cross-heads 29 and a pair of small bearing blocks 38 with- 35 in which the ends of said shaft 32 are journaled. The bearing blocks 38 are slotted at their sides to slidably fit about the bars 25a and 26a. The flexible blades 34 of the brush drum also serve to scrape off excess paint 40 from the die 19 and to keep the material in the hopper thoroughly mixed. The upper bearing blocks 17 and 18 are adapted to be held rigidly in their proper adjusted positions by a pair of bolts 39 and 40 supported 45 upon the tops of the frames 12 and 13, as by angle members 41 and 42.

In order to transmit the rotary motion of the die 19 to the drum 33, the upper shaft 32 carries a pair of collars 43 and 44 having 50 grooved sections 45 on their peripheries forming pulleys for a round belt 46, the lower end of which is seated within a groove 47 of a larger collar 48 rigidly mounted on the ends of the shaft 16a of the upper cylindrical die.

55 In order to cause the die 19 and the transfer roll 20 to oscillate when the bed plate 25 is reciprocated, a pair of flexible flat metal belts 49 and 50 are provided at each end of the machine. The belts 49 are connected as 60 by screws 50a to a pair of enlarged flanges 51 provided on the transfer roll shaft 18a outside of the transfer roll 20. The belts 49 then pass down vertically and around a pair of idle pulleys 52, from which they pass horizontally toward the right-hand end of the bed 65

plate 25, as viewed in Figs. 1 and 2. The extremities of said belts 49 are connected to tension-adjusting take-up bolts 53 mounted in hollow threaded lugs 54 at the ends of the bed plate 25.

70 Nuts 55 and 56 are located on each of said bolts 53 to permit the desired adjustments to be made. The belts 50 are similarly connected to enlarged flanges 57 on the upper die shafts 16a and then pass down and around idle pulleys 58 and have their extremities joined to similar tension adjusting take-up bolts 59 at the other end of the bed plate.

Operation

80 By means of the above construction, whenever the operator pushes the sliding bed 25 from left to right or vice versa, the drum 33, the die 19, and the transfer roll 20 will be oscillated causing the luminous paint to be 85 fed into the engraved recesses 60 cut into the surface of the cylindrical die 19.

The excess paint will be wiped off automatically by the flexible blades 34, and the paint will then be delivered to the cylindrical surface of the transfer roll 20, which is in contact with the die 19. Continued rotation of said roll 20 will then print the paint upon the dial 24.

90 It will be understood that the above described construction insures that the rotary surface speed of the face of the transfer roll 20 will be maintained at all times exactly equal to the sliding speed of the bed plate 25.

95 In the modified form of the invention shown in Fig. 5, a larger hopper 61 is employed for containing a correspondingly greater quantity of the luminous paint. Within the hopper 61 are a pair of horizontal spindles 61a and 62 upon which are mounted 100 a pair of brush drums 63 and 64 respectively. Surrounding the drums 63 and 64 is a continuous strip 65 having on its periphery a plurality of flexible teeth 66 for forcing the paint into the cuts of the cylindrical die 19, removing 105 the excess therefrom, and also serving to mix the paint within the hopper 61.

110 While the invention has been herein disclosed as a manually-operated machine, it will be understood that the bed plate 25 may be reciprocated by any other suitable source of external power within the spirit and scope of the invention.

115 While there have been disclosed in this specification two forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims.

120 Having thus fully described the invention,

what is claimed as new, and for which it is desired to secure Letters Patent, is:

1. In a machine for printing luminous dials, a hopper for containing a supply of paint, a rotary die beneath said hopper, a rotary drum having resilient blades in contact with said die in said hopper for forcing paint into said die and for removing the excess therefrom, a rotary transfer roll in contact with said die, and a dial-holding bed plate reciprocable beneath said transfer roll, whereby the paint will be transferred from said die to said dial.

2. In a machine for printing luminous dials, a hopper for containing a supply of paint, a rotary die beneath said hopper, means in said hopper for forcing paint into said die and for removing the excess therefrom, a rotary transfer roll in contact with said die, a dial-holding bed plate reciprocable beneath said transfer roll, whereby the paint will be transferred from said die to said dial, and means operated by the movement of said bed plate for rotating said die and transfer roll, said die and roll being driven by and connected with said means.

3. In a machine for printing luminous dials, a hopper for containing a supply of paint, a rotary die beneath said hopper, a drum in said hopper for forcing paint into said die, a rotary transfer roll in contact with said die, and a dial-holding bed plate reciprocable beneath said transfer roll, whereby the paint will be transferred from said die to said dial, and means for rotatively connecting said drum and die.

4. In a machine for printing luminous dials, a hopper for containing a supply of paint, a rotary die beneath said hopper, means in said hopper for forcing paint into said die and for removing the excess therefrom, a rotary transfer roll in contact with said die, a dial-holding bed plate reciprocable beneath said transfer roll, whereby the paint will be transferred from said die to said dial, and means for adjusting the pressure between said die, transfer roll, and dial.

5. In a machine for printing luminous dials, a pair of upright frames, a cylindrical die journaled in said frames, a yieldable transfer roll in contact with said die and also journaled in said frames, dial-holding means in contact with said transfer roll, means for feeding luminous paint to said die, and means for manually reciprocating said dial-holding means to cause the paint to be transferred by said roll from said die to said dial, said die and roll being driven by and connected with said means.

6. In a machine for printing luminous dials, a pair of upright frames, a pair of shafts journaled in said frames, a tubular die and a tubular transfer roll mounted on said shafts and being in contact with each other, means for feeding luminous paint upon said

die; a reciprocable dial-carrying bed plate for holding said dial in contact with said transfer roll, pulleys on each of said shafts, and belts each connected at one end to one of said pulleys and at the other end to said bed plate for causing oscillation of said die and transfer roll when said bed plate is reciprocated.

7. In a machine for printing luminous dials, a pair of upright frames, a pair of shafts journaled in said frames, a tubular die and a tubular transfer roll mounted on said shafts and being in contact with each other, means for feeding luminous paint upon said die, a reciprocable dial-carrying bed plate for holding said dial in contact with said transfer roll, pulleys on each of said shafts, and belts each connected at one end to one of said pulleys and at the other end to said bed plate for causing oscillation of said die and transfer roll when said bed plate is reciprocated, and means for adjusting the tension of said belts.

8. In a machine for printing luminous dials, a pair of upright frames, a pair of shafts journaled in said frames, a tubular die and a tubular transfer roll mounted on said shafts and being in contact with each other, means for feeding luminous paint upon said die, a reciprocable dial-carrying bed plate for holding said dial in contact with said transfer roll, pulleys on each of said shafts, and belts each connected at one end to one of said pulleys and at the other end to said bed plate for causing oscillation of said die and transfer roll when said bed plate is reciprocated, means for adjusting the tension of said belts, and idle rolls journaled in said upright frames to guide said belts.

9. In a machine for printing luminous dials, a frame, a paint-receiving die, a transfer roll in contact with said die, means for holding a dial in contact with said transfer roll, a hopper for feeding luminous paint to said die, said hopper carrying a continuous belt mounted on a pair of drums for forcing said paint into the engraved recesses in said die and wiping the excess paint therefrom.

10. In a machine for printing luminous dials, a frame, a paint-receiving die, a transfer roll in contact with said die, means for holding a dial in contact with said transfer roll, a hopper for feeding luminous paint to said die, said hopper carrying a continuous belt mounted on a pair of drums for forcing said paint into engraved recesses in said die and wiping the excess paint therefrom, said belt having flexible blades on its periphery.

11. In a machine for printing luminous dials, a frame, a cylindrical paint receiving die, a soft cylindrical transfer roll in contact with said die, a reciprocating bed plate for holding a dial in contact with said transfer roll, and means on said frame for slidably

supporting said bed plate, said die and roll being driven by and connected with said bed plate.

In testimony whereof, we have affixed our signatures to this specification.
